CLAIM

The ornamental design for a cradle for infant carrier, as shown and described.

DESCRIPTION

FIG. 1 is a perspective view of a cradle for an infant carrier showing my new design, the broken lines are for environmental purposes only and form no part of the claimed design;

FIG. 2 is a front elevational view thereof;

FIG. 3 is a right side elevational view thereof;

FIG. 4 is a rear elevational view thereof;

FIG. 5 is a top plan view thereof; and,

FIG. 6 is a bottom plan view thereof.
